BRAKE DRUM

Leonard Troy, 5 Pen-Y-Bryn Drive, Scranton, Pa.

Filed Apr. 19, 1963, Ser. No. 74,526

Term of patent 14 years

(Cl. D14—30)

FIG. 1

FIGURE 1 is a perspective view looking into the front of a brake drum, showing my design;

FIGURE 2 is a rear elevational view thereof; and

FIGURE 3 is a section taken on line 3—3 of FIGURE 2.

The dominant features of my design reside in the portion shown in full lines.

I claim:

The ornamental design for a brake drum, as shown and described.
